US0D1009880S

(12) **United States Design Patent** (10) **Patent No.:** **US D1,009,880 S**
(45) **Date of Patent:** **** Jan. 2, 2024**

(54) **DISPLAY SUPPORT**

(71) Applicant: **Anhui Hongjie Ergonomic Technology Co., Ltd**, Xuancheng (CN)

(72) Inventor: **Xiaojie Chang**, KunShan (CN)

(73) Assignee: **ANHUI HONGJIE ERGONOMIC TECHNOLOGY CO., LTD**, Xuancheng (CN)

(**) Term: **15 Years**

(21) Appl. No.: **29/799,094**

(22) Filed: **Jul. 13, 2021**

(30) **Foreign Application Priority Data**

Apr. 13, 2021 (CN) 202130206709.8

(51) **LOC (14) Cl.** **14-02**
